UNITED STATES PATENT OFFICE

CHAUNCEY A. HAGER, JR., OF ORD, NEBRASKA

POWER-OPERATED ICE-CREAM FREEZER

Application filed September 18, 1929. Serial No. 393,409.

This invention relates to an ice cream freezer and has relation more particularly to a device of this kind especially designed and adapted for use in connection with power operated mechanism.

It is an object of the invention to provide a device which may be readily attached to and detached from the wringer driving mechanism of a power operated washing machine.

A further object of the invention is to provide a freezer for household use, the mechanism of which is positioned below the device, thereby facilitating an inspection of the cream during the freezing operation thereof.

The invention consists in the details of construction and in the combination and arrangement of the several parts of my improved freezer whereby certain important advantages are attained and the device rendered simpler, less expensive and otherwise more convenient and advantageous for use as more fully set forth herein.

Other and further objects and advantages of my invention will be obvious from the following detailed description reference being had to the accompanying drawing wherein:

Figure 1 is a view partly in section and partly in elevation illustrating an ice cream freezer attached to the wringer shaft of a power operated washing machine constructed and assembled in accordance with an embodiment of my invention.

Figure 2 is a side elevation of a novel attaching, driving and supporting means employed; and

Figure 3 is a top plan view of an agitator shaft holding means parts thereof being broken away.

Referring now to the accompanying drawing for a more particular description in which like numerals of reference designate like or corresponding parts the numeral 10 indicates a washing machine provided with a support or legs 11 and having a motor 12 which is adapted to drive a wringer shaft 13 through a system of gears 14, not shown, contained within a housing 15.

The upper end of the shaft 13 is provided

with a transversely positioned pin 16 through which a removable clothes wringing member, not shown, may be selectively attached and detached.

The driving shaft 13 which is positioned within an elongated housing 17 is similarly adapted to drive the new device which comprises a sleeve 18, adapted to be seated over the housing 17 and secured in a stationary position preferably to the body of the washing machine 10 by means of an arm 19 and a bolt or keeper 20.

The sleeve 18 is provided with a flange 21. A metal bucket 23 is secured to the flange 21 by means of rivets 24, the latter being inserted through a collar 25. By this means the rivets or keepers 24 are adapted to secure the bottom 23' of the bucket 23 to the sleeve 18 and it will be understood that a gasket 22 is preferably employed for preventing leakage of ice water.

As best shown in Figure 2, a rotatable shaft 26 is employed for coupling the later described devices to the driving shaft 13. The rotatable shaft 26 of the new device is provided with a bifurcated lower end 27 thereby forming a slot 28 which is adapted to register with the transverse pin 16 of the driving shaft 13.

A bushing 28 is provided for the shaft 26 and is adapted to register with the upper edge of the housing 17 of the shaft 13 for supporting the device thereon.

A cream container 29 is provided with a bottom 30. The side walls of the container 29 extend below its closed bottom 30 as shown in Figure 1 in order that the container may rest upon a flat surface such as a table during the time it is being filled with cream.

The bottom 30 of the container is provided with a downwardly projecting portion 31 which is bifurcated thereby providing a slot 32, within which is received the lug or pins 33 of the rotatable shaft 26.

It will be understood that the rotatable shaft 26 is adapted to have corresponding movements with the driving shaft 13, while being journaled within and supported by the sleeve or housing 17 of the shaft 13. By this means corresponding rotary movements

are provided for the container 29 at all times that the shaft 13 is revolved.

The container is provided with a cover 34 and a stationary agitator shaft 35, the latter having a plurality of outwardly projecting tangs 36 and a plurality of pivotally mounted paddles 37, which, together with the tangs 36, function as agitators for the cream as later described.

- 10 The upper end of the agitator shaft 35 is provided with a portion which is rectangular in cross section as indicated at 38 and as best shown in Figure 3. The portion 38 is adapted to be received within a correspondingly 15 shaped notch 39 of a bar 40, the latter being provided with down turned fingers 41 which, as best shown in Figure 1, are adapted to register with an annular flange 42 formed at the upper edge of the bucket 23.

- 20 By this means the agitator shaft 35 is held stationary with the bucket 23 at all times while the container 29 is rotated.

In operation the freezer is supportingly attached to the shaft 13 and the outer bucket 25 thereof is held stationary by any suitable means such as the bolt 20. The ice cream mixture to be frozen is placed within the container 29 and the cover 34 placed thereon after the container has been placed within the 30 bucket and in register with the driving shaft 26. The detent bar 40 is now moved towards the center of the bucket 23 where it will be detained by reason of its fingers 41 being in register with the flange 42 of the bucket and 35 at this time the latch 43 of the member 40 is closed against the shaft 35, a pivot 44 for the latch 43 being provided for this purpose.

The space between the container 29 and the bucket 23 is now packed with ice and salt and 40 the motor 12 placed in electrical communication with a closed circuit, not shown.

The high speed of the motor 12 is reduced through the gearing 14 and the motion communicated to the container 23 which, by 45 means of its rapid revoluble movement, will cause the cream to become solidified.

From the foregoing description it is thought to be obvious that an ice cream freezer constructed in accordance with my invention is particularly well adapted for use by 50 reason of the convenience and facility with which it may be operated and assembled, and it will also be obvious that my invention is susceptible of some change and modification 55 without departing from the principles and spirit thereof and for this reason I do not wish it to be understood as limiting myself to the precise arrangement and formation of the several parts herein shown in carrying 60 out my invention in practice, except as hereinafter claimed.

I claim:

1. A power operated ice cream freezer comprising an external container for ice, a sleeve 65 projecting downwardly from the bottom of

said container and having a flange secured to the bottom of the container, a cream receptacle rotatably mounted within said container, a tubular housing below said container enveloped by said sleeve, a drive shaft within said housing spaced therefrom, a drive mechanism connected to said drive shaft, means between said drive mechanism and the sleeve for holding the sleeve and ice receptacle against rotation, and a rotary coupling member 70 between said drive shaft and cream receptacle having a part supported on said housing and in turn supporting said flange and sleeve upon the housing.

2. A power operated ice cream freezer comprising a stationary external ice container, a rotary internal cream receptacle, a sleeve extending downwardly from the bottom of said external container and secured to the container, a housing for receiving and supporting said sleeve and the container, a drive shaft within said sleeve, a drive device for said shaft, means between said sleeve and the drive device for maintaining the sleeve and container against rotation, and coupling 80 means between said drive shaft and the cream receptacle extending through said sleeve and housing and through the bottom of the container, said coupling means having a flange resting upon said housing and for supporting 85 the stationary container.

3. A power operated ice cream freezer comprising an external ice container, a flanged sleeve secured to the external bottom of the container and extending downwardly therefrom, a housing receiving said sleeve, a drive shaft within said housing, drive mechanism for rotating said drive shaft, means connected between said sleeve and the drive mechanism for preventing the rotation of 90 the sleeve and container, coupling means engaged with said drive shaft within the housing and having a flange resting rotatably upon said housing and for receiving and supporting the flange of said sleeve and the container, and a cream receptacle rotatably mounted within said container and coupled to the upper portion of said coupling means.

In testimony whereof, I have affixed my signature.

CHAUNCEY A. HAGER, JR.
